ROTARY CARD INDEX

George C. Bruen, Chicago, Ill., and Karl H. Miller, North Canton, Ohio, assignors to Diebold Incorporated, Canton, Ohio, a corporation of Ohio

Application March 15, 1944, Serial No. 526,532

6 Claims. (Cl. 129—16)

1

The invention relates generally to rotary card indexes wherein cards are mounted more or less radially on a wheel having a circular rail, or circular rail segments, with an enlarged head by means of keyhole-shaped slots in the bottom edges of the cards.

More particularly, the invention relates to improvements in the wheel construction, the pull ring for the wheel and the bearings for the wheel of rotary indexes such as shown in the prior Bruen Patents Nos. 2,168,323 and 2,235,736.

In the constructions of said prior Bruen patents, limitations are imposed upon the size or width of card that may be mounted on the rail. In the first, the side flanges on the wheel prevent wider cards than will fit between the side flanges from being mounted on the wheel. In the second, cards wider than substantially the width of cards shown therein, may twist or angle out of proper position laterally of the rail and across the wheel face to such an extent as to become disengaged from the rail. In the latter instance, the undesirable angling or twisting may occur because of the short length of the permanent end stop on one end of each rail segment. The functions of these end stops are to divide the cards into sections on the wheel, and also to form a card stop for the segment transferred when transferring the segment from a wheel to a tray or vice versa.

Moreover, in the constructions of each of said prior patents, when a rail segment is removed for any purpose, and if the wheel is then rotated, cards on one of the rail segments adjacent the space left by the segment removed may fall off of the exposed or open end of the rail segment on the wheel, thereby causing a disturbance in the continuity of record cards on the wheel.

Another difficulty sometimes encountered in the operation and use of rotary indexes such as shown in said prior patents, is that sometimes considerable time is consumed in locating the first, primary or initial cards of the groups of cards carried by the wheel.

Also, difficulties have been encountered in the assembly of the wheel in a case or cabinet with a cover where the cover rotates on substantially the same axis as that of the wheel.

Accordingly, it is an object of the present invention to provide a wheel construction for a rotary card index which avoids or eliminates the described difficulties sometimes encountered in using said prior constructions.

Also, it is an object of the present invention to provide an improved wheel construction for

2

a rotary card index, which, in cooperation with circular rail segments carried by the wheel, permits a wide range of width of cards to be mounted on the rail segments and yet prevents angling, tilting or twisting of the cards, regardless of width, across the wheel face or laterally of the rail, sufficient to dislodge the cards from the rail.

Moreover, it is an object of the present invention to provide the smooth substantially cylindrical card index wheel surface on which cards rest that are mounted on circular rail segments removably carried by the wheel, with a projecting ear laterally opposite each end of the integral stop or partition member formed at one end of each rail segment, for preventing twisting of cards, particularly of the larger widths.

Also it is an object of the present invention to provide an improved wheel construction for a rotary card index having removable circular card carrying rail segments, in which cards will not fall off of any rail segment on the wheel when one or more rail segments are removed from the wheel, irrespective of the position or movement of the wheel and of the location of any space on the wheel left by any removed rail segment.

Moreover, it is an object of the present invention to provide a card index wheel surface on which cards rest that are mounted on circular rail segments removably carried by the wheel, with ears projecting laterally opposite each division point between adjacent ends of adjacent rail segments, for preventing cards on any rail segment mounted on the wheel from falling off of such rail segment upon removal of any adjacent rail segment from the wheel, irrespective of the position of or movement of the wheel.

Also, it is an object of the present invention to provide means visible to the eye or arresting to the touch of the operator to indicate, at the briefest glance or upon rotation of the wheel without reference to the cards carried thereby, the location of the first, primary or initial group of cards thereon.

Furthermore, it is an object of the present invention to provide a pull ring construction for the wheel of a rotary card index in which the pull ring may be formed of an extruded tube of thermoplastic material with a joint, and in which the joining means also provides an eye or touch signal indicating the location of the primary group of cards on the wheel.

Moreover, it is an object of the present invention to provide an improved bearing construction for a wheel member of a rotary index housed

in a cabinet with a rotary cover rotatable about the wheel axis in which the bearings and mounting for the wheel and cover are interrelated but independently adjustable for facilitating individual alignment of the wheel and cover in assembling the rotary index.

Finally, it is an object of the present invention to generally improve the construction, flexibility and operation of a rotary card index.

These and other objects may be obtained, the stated results achieved, and the described difficulties overcome, by the devices, constructions, arrangements, improvements, combinations, parts and elements which comprise the present invention, the nature of which is set forth in the following general statement, preferred embodiments of which are set forth in the following descriptions and are shown in the drawings, and which are particularly and distinctly pointed out and set forth in the appended claims forming part hereof.

The nature of the improvements in rotary card indexes of the present invention may be stated in general terms as preferably including in a card filing device, a wheel having a substantially cylindrical outer surface upon which the lower edges of cards mounted on the wheel may rest; a plurality of rail segments removably mounted on the wheel each comprising a head, a flange, and a partition, divider or stop member at one end of the head and flange and forming a substantially continuous circular rail on the wheel arranged to receive a multiplicity of cards having keyhole-shaped slots at their lower edges; ears projecting from the wheel surface laterally opposite each end of the divider member of each rail segment; a pull ring associated with the wheel preferably formed of tubular thermoplastic material with a joint therein of specially colored material and preferably of slightly different shape in cross section than the remainder of the pull ring; a cabinet within which the wheel is mounted having a rotatable cover; means mounting the cover and wheel within the cabinet on substantially the same axis; and said mounting means being relatively adjustable whereby the wheel and cover may be individually aligned during assembly thereof.

By way of example, preferred embodiments of the improved construction are illustrated in the accompanying drawings forming part hereof, wherein

Figure 1 is a vertical section of a rotary index of the type shown in Bruen Patent No. 2,235,736, but illustrating the improved wheel construction of the present invention;

Fig. 2 is a fragmentary view looking down on the top of the wheel shown in Fig. 1;

Fig. 3 is a fragmentary perspective view of the wheel shown in Figs. 1 and 2 with cards removed;

Fig. 4 is a section through the joint at the pull ring taken on the line 4—4, Fig. 1;

Fig. 5 is a section taken on the line 5—5, Fig. 1, illustrating the bearing construction; and

Fig. 6 is a section through a modified type of pull ring.

Similar numerals refer to similar parts throughout the drawings.

Referring particularly to Figs. 1, 2 and 3, there is shown a card mounting wheel 10 of a type shown in Bruen Patent No. 2,235,736 preferably comprising two halves 11 and 11a forming a hub 12, spokes 13 and a smooth, substantially cylindrical surface 14 on which cards rest that are mounted on the wheel. The wheel halves 11 and

11a are preferably bolted together by bolts 15 and may also be secured together by the end portions 16 of L-shaped rods 17 on which the pull ring 18 is mounted.

5 The edges of the rim portions of the wheel halves 11 and 11a are spaced apart at 19 to form an annular slot 20 for receiving the flanges 21 of rail segments or sections 22. Each rail segment 22 preferably comprises the flange 21, an enlarged head 23, and an integral stop or partition member 24 formed at one end thereof.

Each rail segment 22 is provided with slots (not shown) adapted to engage the rods 16 and locking latches (not shown) for detachably mounting the rail segments 22 on the wheel 10, as shown in said Patent No. 2,235,736. Thus, when the rail segments 22 are all mounted on the wheel 10, they form a substantially continuous circular rail on the wheel.

15 A plurality of cards 25 having keyhole-shaped slots 25a at their lower edges may be removably mounted on the rail segments 22, as well shown in Figs. 1 and 2; and the bottom edges of the cards rest on the smooth, substantially cylindrical card index wheel surface 14 when the cards are at the top of the wheel. Of course the cards at the bottom of the wheel hang from the rail flange and head 21 and 23 by the keyhole-shaped slots 25a.

20 A function of the stops 24 on each rail segment is to limit the shifting of the cards 25 to a relatively short arcuate space around the wheel 10; and furthermore to provide a stop or retaining member for holding the cards 25 on the rail 22 when the rail segment with cards thereon is removed from the wheel 10 for being transferred to a desk tray or the like.

25 For many reasons, the stop member 24 should have the approximate shape, size and length shown. However, the stop member 24 of such length is not sufficient to prevent angling or twisting or tilting of the cards substantially out of a normal position transverse of the rail 23 and across the wheel surface 14, when very wide cards 25 are mounted on the wheel.

30 Thus, referring to Fig. 2, the normal position of the cards in this figure is vertical at substantially right angles to the rail 23 and if these cards are angled to a substantial degree out of vertical, they may twist off or become dislodged from the rail head 23. When the cards 25 have a width of up to the approximate width of the wheel surface 14, the end stops 24 prevent too much angling. However, it is frequently desirable to use cards on a rotary index having a wide range of widths such as the cards 25 shown that overhang the edges of the wheel.

35 In order to prevent undesirable angling of such wide cards, we have provided, in accordance with the present improvements, a series of ears 26 projecting outwardly of the wheel surface 14, one ear opposite each end of each segment stop portion 24. The ears 26 in cooperation with the stop members 24, prevent any substantial twisting or angling of wide cards 25 sufficient to permit dislodgment of the cards from the rail head 23.

40 Thus, the smooth substantially cylindrical surface 14 of the wheel 10 permits cards of any width to be mounted on the wheel, and the ears 26 prevent undesirable angling of the cards. Even wider cards than those shown in Figs. 1 and 2 may be mounted on the wheel by increasing the width of the cabinet and by spacing the pull ring 18 further from the wheel edge.

45 Moreover, the ears 26 opposite each end of each

5

segment stop portions 24, are also located at each side substantially opposite the junction between adjacent rail segments and therefore also function as a stop for the end of any rail segment. Thus, referring to Fig. 3, an entire rail segment 22 with its stop 24 is shown at the left of the view and a portion of another rail segment 22 with its stop 24 (at the left end thereof) is shown at the right of the view. When the rail segment 22 at the right of Fig. 3 is removed from the wheel, the open end of the adjacent rail segment at the junction between adjacent segments at the left of Fig. 3 is exposed, and any cards on such segment, on rotation of the wheel would fall off of the segment; except that the two ears 26 at the right of Fig. 3, and opposite the junction between the adjacent rail segments referred to, prevent the cards from falling off of the rail segment still mounted on the wheel.

Thus, the ears 26 not only function to keep the cards from twisting off of the rail segments, but also to retain cards on rail segments on the wheel when one or more rail segments are removed from the wheel.

In accordance with the present invention, the pull ring 18 is preferably formed of a tube 18a (Fig. 4) of extruded thermoplastic material. In forming the ring 18 from such tube 18a, another tubular member 18b is telescoped within the open ends 18c of the tube 18a to secure the ends together and form a ring shape.

In so forming the pull ring, a bead 18d of thermoplastic material of a different color than the material of tube 18a is interposed between the ends 18c. The bead 18d has a slightly enlarged cross section as shown. The pull ring 18a may be white and the material of the bead 18d may be blue or red or black or some other color contrasting with the color of the pull ring so as to provide a visible signal to the eye. The slightly different cross sectional shape of the bead 18d likewise provides an arresting signal to the touch of the operator in turning the wheel 10 by pulling along the pull ring 18.

In arranging the cards 25 on the wheel, the group of "A" cards or No. 1 cards or the initial or primary group of cards arranged on the wheel, may be located opposite the signal means 18d so that the operator, at the briefest glance, or upon rotation of the wheel without reference to the cards carried thereby, may quickly turn the wheel to the location of the first or primary or initial group of cards thereon. This saves considerable time in the continuous operation and use of rotary card indexes.

Accordingly, the improved pull ring construction provides an inexpensive way to make a satisfactory pull ring from tubular thermoplastic material without the difficulty of making an accurate and smooth joint; and the joint of slightly different shape and of different contrasting color serves as the initial index for the wheel.

Furthermore, the pull ring may be formed in its outer surface with a very shallow recessed slot 18e (Fig. 6) if desired, for receiving flexed paper index indicators 18f for further indexing the cards 25 carried by the wheel 10.

The hub 12 of the wheel 10 is secured to an axle 27, preferably by screws 28. The wheel 10 may be housed in a cabinet having side walls 29 and a rotatable cover member 30. In accordance with the present improvements, a disc bearing 31 having a reduced boss 32, is mounted in a recess 33 in each side wall 29 so that the boss 32 forms a bearing for rotatably mounting the cover 30. In

6

assembling the cabinet and cover, the disc members 31 may be separately adjusted and fitted with the side walls 29 and the cover 30 to properly align and locate the cover.

5 A flat plate 34 with a top cross bar 35 and a U-shaped hanger 36 secured to the cross bar 35 by screws 37, forms a support, bearing and hanger for each end 38 of the wheel axle 27, whereby the wheel is mounted within the cabinet. The plates 34 are adjusted to properly align the wheel 10, and are then secured by screws 39 to the disc members 31. The screws 39 may be and preferably are long enough to engage not only the disc members 31, but also the cabinet side walls 29.

10 With this improved construction, a very inexpensive bearing and mounting is formed for both the wheel 10 and the rotatable cover 30, so that they may rotate about substantially the same axis while permitting individual adjustment and alignment of the wheel 10 and cover 30 when assembling the same with the cabinet.

Accordingly, the present invention provides very inexpensive and simple changes in the construction of a rotary card index of the type shown in Patent No. 2,235,736 for eliminating difficulties 25 which have been encountered in the manufacture and use of the same; provides a rotary card index on which cards of a great range of widths may be mounted; provides a rotary index with signal means visible to the eye or arresting to the touch for indicating the primary group of cards on the wheel; and provides a simplified bearing construction for readily assembling a rotary card index wheel and a cover therefor in a cabinet for the same.

30 The embodiments of the present improvements illustrated and described herein are by way of example, and the scope of the present invention is not limited to the exact details of construction of the various parts. When the term "rail" is used herein and in the appended claims, that term is used in its broadest sense, irrespective of the character of its cross section.

Having now described the features of the invention, the construction, operation and use of embodiments thereof, and the advantageous, new and useful results attained by the improved construction; the new and useful parts, elements, combinations, improvements, constructions and 40 devices, and reasonable mechanical equivalents thereof obvious to those skilled in the art, are set forth in the appended claims.

We claim:

45 1. In a rotary card index, a rotatably mounted wheel-like support having a smooth, substantially cylindrical card index wheel surface on which cards rest, a plurality of circular rail segments removably carried by the wheel; each rail segment comprising a flange, a head and a partition 50 secured to and formed at one end thereof; and an ear secured to the wheel and projecting from the wheel laterally opposite each end of each partition.

55 2. In a rotary card index, a rotatably mounted wheel-like support having a substantially cylindrical outer surface upon which the lower edges of cards mounted on the wheel may rest; a plurality of rail segments removably mounted on the wheel, each comprising a head, a flange, and a partition member secured to and extending laterally of the head at one end of the segment; said segments when assembled on the wheel forming a substantially continuous circular rail arranged to receive a multiplicity of cards having keyhole-shaped slots at their lower edges; and an ear

secured to the wheel and projecting from the wheel surface laterally opposite each end of the partition member of each rail segment.

3. In a rotary card index, a rail comprising a head and flange constructed and arranged to receive a multiplicity of cards having keyhole-shaped slots at their lower edges, said rail including a plurality of removable rail segments arranged end to end with a junction between adjacent rail segments, each rail having a lateral stop secured thereto at one end thereof, a wheel on which the rail segments are mounted having a substantially cylindrical smooth card supporting wall associated with the rail, and an ear secured to the wheel and projecting outwardly of said wall on each side of the rail substantially opposite each junction.

4. In a rotary card index, a rotatably mounted wheel-like support having a smooth card index wheel surface on which cards rest, a plurality of rail segments each having an integral stop at one end thereof and arranged end to end on and removably carried by the wheel, and an ear secured to the wheel and projecting from the wheel on each side of the rail substantially opposite each junction between adjacent rail segments.

5. In a rotary card index, a rotatably mounted wheel-like support having a surface on which cards rest, a plurality of rail segments each having an integral stop at one end thereof and arranged end to end on and removably carried by the wheel, and means secured to and projecting

from the wheel laterally of each end of each rail segment for retaining cards on a rail segment on the wheel when an adjacent rail segment is removed from the wheel.

6. In a rotary card index, a rotatably mounted wheel-like support having a smooth arcuate card index wheel surface on which cards rest, a plurality of arcuate rail segments each having an integral stop at one end thereof and arranged end to end on and removably carried by the wheel and each rail segment having a flange and a head, and means secured to and projecting from the wheel laterally of each junction between adjacent rail segments for retaining cards on any rail segment on the wheel when an adjacent rail segment is removed from the wheel.

GEORGE C. BRUEN.
